[57] ABSTRACT

Apparatus in the nature of a jig for fabricating wood trusses providing a stationary support means, upon which the members of the wood truss are disposed. Truss plates are placed at the joints of the members of the wood truss and the teeth thereof embedded therein by means of a hydraulic press. The stationary support means includes a plurality of metallic slats, having a degree of flexibility, upon which the members of the wood truss are properly positioned. The slats are so constructed as to be mounted and removed from the stationary support means with facility and are also so structured, that upon application of vertical forces to the truss plates to drive them into the members of the truss, the pressures resulting therefrom strengthen the entire unit and provide support along the transverse centers of each slat, and also at and adjacent to the longitudinal edges of each slat. The longitudinal edges of the slats are spaced apart and removable means operatively extend between adjacent slats for anchoring fixtures in proper position on the slats to abut and maintain the wooden members of the truss in the desired and necessary relative positions for fabrication of the truss components into a unitary building structure.

APPARATUS FOR PRE-FABRICATING WOOD STRUCTURES

This invention relates broadly to the art of fabricating wooden truss structures for use in the building arts, and in its more specific aspects, it relates to a jig of unique character, upon which the wooden members of the truss are properly positioned with metal truss plates being positioned at the joints of the wooden members for embedding therein; and the nature and objects of the invention will be readily recognized and understood by those skilled in the arts to which it relates in the light of the following explanation and detailed description of the accompanying drawings illustrating what I at present believe to be preferred embodiments or mechanical expressions of my invention from among various other forms, arrangements, combinations and constructions, of which the invention is capable within the spirit and scope thereof.

The conventional wooden truss, which is now widely used in the building trades, generally consists of a plurality of wooden members, which are joined together at the abutting ends of said members, to form a completed usable truss of the proper dimensions. The members of the truss, such as the chord and web members, are joined together at their abutting portions by means of metal truss plates, which customarily include a body portion from which are struck a plurality of teeth or prongs which are embedded in a portion of each abutting member to connect such members together. Various types of pressing means have been employed for this embedding operation, such as pressing rollers and hydraulic and pneumatic presses.

Those skilled in this art will recognize that the accurate and proper positioning of the wooden members of the truss on the supporting table or platform of the jig is of the utmost importance, so that the truss, when completed, will be properly dimensioned.

It is customary in this discipline to use a variety of types of fixtures which are so affixed to the bed or platform of the jig and are disposed in the proper abutting relationship with the wooden members of the truss at various points therealong to maintain the said members in the proper and necessary positions during the fabricating operation. Since trusses of variable dimensions must be fabricated it will be appreciated that the maintaining fixtures for the wooden members of the truss must have an adjustable characteristic relative to the truss supporting portions of the jig, so as to be in the proper positions for abutting the wooden members of the truss to maintain them in the necessary positions during the fabrication operation. It has been my experience in this art that many arrangements have been resorted to in order to provide adjustability in these fixtures, and the majority of such arrangements, of which I am aware, are relatively complex in nature requiring considerable time in properly adjusting them.

It has been one of my prime purposes in the evolution of this invention to produce fixtures for these purposes which are adjustable relative to the supporting surface of the jig and to the truss members, with facility. The mounting and adjustable arrangement of these fixtures is such that little time is required in properly adjusting them and the mounting and securing means for the fixtures is simple and of a non-complex nature.

In the fabrication of wooden trusses, I have provided a stationary platform, upon which is mounted certain

members, which will be discussed in detail hereinafter, and it is upon these members that the truss elements are laid in their proper positions with the metal truss plates positioned at the joints thereof, and I propose utilizing an hydraulic, or the like, press for embedding the metal truss plates in the wooden members of the truss at the joints thereof, the press being movable over the wooden members of the truss and operable at the desired points thereover to cause embedment of the metal truss plates in the wooden members of the truss at the joints thereof. The actual surfaces upon which the wooden members of the truss are laid comprise, generally a plurality of metallic slat members, which are supported in spaced position longitudinally with respect to the platform, and are formed with a degree of flexibility and due to this particular slat characteristic, structure and configuration, when the forces generated by the operation of the press are applied to the metal truss plates, each slat unit is strengthened, and particularly the slat's centers and outside edges, all as will become apparent as this description proceeds.

In the actual use and operation of the jig, the possibility of slat breakage exists and with this in mind, I have so formed the slats and the means upon which they are mounted which function to support and space the slats from the platform, that any individual slats which may have been damaged, may be easily removed from the supporting means and a new slat mounted in operative position on the supporting means with ease.

In the development of a relatively simple jig arrangement for use in the fabrication of wooden trusses, I have not sacrificed economies in the construction and operation of the jig, and I have also provided a jig of this character which is easy to operate, and to properly position and maintain the wooden truss members in the necessary positions thereon, thereby substantially reducing labor and operational costs in the fabrication of wooden truss members.

With the foregoing general objects, features and results in view, as well as certain others which will be apparent from the following explanation, the invention consists in certain novel features in design, construction, mounting and combination of elements, as will be more fully and particularly referred to and specified hereinafter.

Referring to the accompanying drawings:

FIG. 1 is a view, in perspective, of a slat with parts thereof broken away.

FIG. 2 is a vertical sectional view of a jig with parts thereof broken away.

In the accompanying drawings, I have used the numeral 1 to designate, in its entirety, one of the slats, the numeral 3 to designate the hydraulic press, or other type press, which is operable longitudinally of the jig into position for pressing metal truss plates into embedded fabricating position within the wooden members of the truss at the joints thereof. Numeral 5 has been selected to designate, in its entirety, the adjustable anchoring means for the base plates of the fixtures, which are positioned so as to be in maintaining abutment with the wooden members of the truss.

I provide a platform, or jig, tabletop in the form of an elongated metal plate 7. The substantially rigid supporting platform 7 is on the order of one-fourth inch in thickness, since this has been found to be suitable to withstand pressures to which it is subjected in the pressing operations. In most operations, it has been found

suitable if the platform 7 is approximately 12 ft. wide, and it may be formed of any length found desirable in the fabricating operation.

At spaced intervals, longitudinally of the platform 7, I have fixed thereto T bars, designated generally by the numeral 11, such T bars comprising a stem 13, which is fixed, as by welding 15, to the platform 7 and a head 17 is formed on the opposite end of the stem 13 of the T-bar 11.

The slats 1 are removable from their supporting means, as will be explained hereinafter, and are roll formed, providing the jig table top, upon which the truss members are positioned in the fabricating operation. A slat 1 is provided for each T-bar 11 in the jig assembly and each slat comprises a flat bed surface 19, which is substantially 6 ft. in transverse width and its length, or longitudinal dimension, is substantially the same as the width of the platform 7 and the length of the T-bars 11. Each slat at each longitudinal end thereof is rolled over on itself as at 21, providing a longitudinally extending slat edge portion, comprising an upper section 23 and a lower section 25 rolled to be in abutment with the upper section 23. It will be appreciated that this edge structure reinforces each longitudinal edge of each slat. The lower section 25 at its inner end depends inwardly and downwardly providing an inclined longitudinally downwardly extending supporting flange 27, the lower end 29 of which is in abutment with the top surface of the platform 7, forming a bearing point, or edge. From the bearing point 29, a longitudinally extending flange 31 extends upwardly. The supporting flange 31 ends at 33, the longitudinally extending end or edge, 33 being disposed beneath the cross base 17 of the T-bar. In normal position, when the press is not operating, the edges 33 of each flange 31 are spaced from the head 17. Preferably, the included angle between the flanges 27 and 31 is on the order of 90°, while the angles between such flanges 27 and 31 and the platform 7 is each on the order of 41½°.

It will now be clear that each slat is formed with two longitudinally extending bearing points, or angled edges 29, and that one is on one side of the T-bar 11 and the other on the opposite side thereof, and that each is outside a projected vertical plane from the head 17. It will also now be clear that each slat is formed with a degree of flexibility.

In order to remove a slat 1, which may have been damaged, it is merely necessary to slide it longitudinally of the T-bar 11, so that it will slide off the end thereof. To assemble a new slat 1, it is merely necessary to slide said slat on the T-bar with the flat bed surface of the slat sliding along the head 17 and with the flanges 31 of the slat in position beneath the head, as clearly disclosed in FIG. 2 of the drawings.

When the slats are assembled in operative positions in the jig, one slat being provided for each T-bar, it will be recognized that the flat bed surface 19 of each slat rests on the top surface of a head 17 of a T-bar and extends transversely beyond the longitudinal edges of the head, since the width of each slat is greater than the width of the head of the T-bar. It will also be apparent that each slat is provided with two bearing edges 29, being on opposite sides of the T-bar. It will also be evident that the spacing of the T-bars on the platform 7 and the width of each flat bed surface 19 of each slat are such that the longitudinal edges 21 of adjacent slats are spaced apart, leaving a free area 35 between the

longitudinal edges of adjacent slats, all as is clearly illustrated in FIG. 2 of the drawings.

As I have stated above, jigs of this character are designed for the fabrication of trusses of varying dimensions and it is thus necessary to provide some means on the truss supporting surfaces, which are adjustable so as to be movable into abutting position with the wooden members of the trusses. Various types of fixtures which are movable into abutting relation with the wooden truss members, have been devised and they may take various forms, such as camming mechanisms, and the like. In my invention, I may employ various types of fixtures and since the fixtures, per se, form no part of this invention, I have not illustrated them in the drawings. Anyone skilled in this art will be aware of several types of fixtures. I provide a fixture base plate 37, which, in a manner to be described, is adjustably or movably mounted on and with respect to the slats 1. Any of the aforementioned suitable types of fixtures for abutting and maintaining the wooden members of the truss in proper position, may be employed and fixed to the fixture base plate 37 in any convenient and suitable manner. Thus, by moving the base plate 37 to various adjustably fixed positions on the bed surfaces 19, of the slats, the fixture or fixtures mounted on the base plate will assume their proper and desired positions with respect to the wooden members of the truss. While I have disclosed only one such fixture base plate, it will be understood that any number of such fixture base plates, with their fixtures mounted thereon, may be used. The mounting and operation of each fixture base plate 37 is the same.

I provide for each fixture base plate 37 a fixture base plate anchor bolt 39, having on one end thereof a head 41 and a washer 43 supported by said head 41. The end of the anchor bolt 39, which is opposite to the end thereof upon which the head 41 is fixed is threaded, as at 45, and threadedly mounts a tightening nut 47. The anchor bolt 39 extends through an aperture which is provided in the fixture base plate 37 and such aperture is positioned over the free area 35, between the longitudinal edges 21 of adjacent slats 1, so that the anchor bolt 39 extends through such area between the edges 21 of adjacent slats. With the anchor bolt extending through the free area and through the aperture in the fixture base plate 37, and with the washer 43 in position relative to the head 41, as shown in FIG. 2, and with the tightening nut 47 threaded on the anchor bolt and into tightened threaded position thereon in engagement with the upper surface of the fixture base plate 37, the washer 43 will be in tight holding engagement with the edges 21 of adjacent slats, and the fixture base plate 37 will be held in proper position with its fixture or fixtures in abutting position with a wooden member of a truss to hold and maintain the wooden member in proper position for the proper position for the pressing operation and the embedment of a metal truss plate into the wood at the joints between the wooden members.

In order to adjust the position of the fixture base plate 37, it is merely necessary to loosen the tightening nut 47, so that the bolt and its assembled elements, along with the fixture base plate 37 and its attached fixtures, may be moved along the free area 35 between adjacent slats to any desirable position, transversely of the jig, in order to place the fixtures in proper wooden member abutting position.

It will be appreciated that any suitable type of press may be used with jig assembly, in order to press the metal truss plates into the wooden members of the truss at the joints of such members. It is customary to place the metal truss plates on both sides of the wooden members of the truss for pressing and embedment therein by the press. Merely by way of example, of one type of press arrangement which I may use, I have illustrated the press 3, having the reciprocating platen 49 which engages the metal truss plates on one side of the wooden truss members, as well as engaging parts of the wooden members.

The press is provided with a lower platen 50, which slidably extends beneath the platform 7, the lower platen 50 being connected to press 3 in any suitable manner, as by extensions 52 from the press 3. The press assembly, including the platen 50 is movable longitudinally of the jig into positions, so that the reciprocating platen 49 is over the metal truss plates, which are to be embedded into the wooden truss members, it being understood that the lower platen 50 moves longitudinally of the jig with the entire press assembly, so that the lower platen is at all times beneath and in the vertical plane of the reciprocating platen 49.

The press assembly is mounted for longitudinal movement with respect to the jig in any manner well known in the art. For instance, the press assembly may be operatively mounted on wheels, which move on a track below and on both sides of the jig. Since the particular operative mounting of the press assembly forms no part of this invention, such operative mounting arrangement has not been shown in detail.

The platform 7 may be supported in any suitable manner as, for instance, by legs which are collapsible by engagement with the press assembly as it moves longitudinally with respect to the jig. In this operation, it would push one leg over and down with another leg following up immediately behind the press assembly. Such arrangements are known in the art and may be followed in this particular instance.

It is also within my contemplation to provide an arrangement of this general character, wherein the press assembly is stationary and the supporting surfaces, including the slats, move horizontally, forwardly and backwardly through the stationary press assembly.

It will be appreciated that when the platen is operated to force the metal plates into the wood, considerable forces and pressures are applied to the wooden members of the truss, the slats 1 and the platform 7. When these various elements are subjected to these pressures, it will be evident that the heads 17 of the T-bars support the slat centers and the edges 21 of the slats are also strengthened and maintained against deformation by the bearing edges 29 and the flanges 27, which support these outside edges of the slats. Thus, the particular slat arrangement and configuration is designed to strengthen the overall slat unit. In some instances during the pressing operation, the forces and pressures may be sufficient to force the edges 33 of the slats into strengthening engagement with heads 17.

I claim:

1. Apparatus for fabricating a wooden truss, wherein a press is used to embed metal truss plates in the wooden members of the truss at the joints thereof, including, in combination, a substantially rigid platform, a plurality of slat support means fixed on said platform in spaced relation and extending thereacross and up-

wardly from said platform, an elongated slat supported on each of said slat support means and providing an upper support surface for the wooden members of the truss.

5 2. Apparatus for fabricating a wooden truss, in accordance with claim 1, wherein the longitudinal edges of adjacent slats are spaced apart.

10 3. Apparatus for fabricating a wooden truss, in accordance with claim 1, wherein said slat support means are elongated and are of substantially the same length as the length of said elongated slats.

15 4. Apparatus for fabricating a wooden truss, in accordance with claim 1, wherein said elongated slats have a degree of flexibility.

5 5. Apparatus for fabricating a wooden truss, in accordance with claim 3, wherein said elongated slats are of greater width than the width of the slat support means.

20 6. Apparatus for fabricating a wooden truss, in accordance with claim 5, wherein said elongated slats have a degree of flexibility and each of said slats includes a surface in supporting engagement with said substantially rigid platform.

25 7. Apparatus for fabricating a wooden truss, in accordance with claim 6, wherein each of said elongated slats is provided with at least two surfaces in supporting engagement with said substantially rigid platform, one of said surfaces being on one side of said slat support means and the other of said surfaces being on the other side of said slat support means.

30 8. Apparatus for fabricating a wooden truss, in accordance with claim 6, wherein a downwardly and inwardly extending flange projects from adjacent each longitudinal edge of each slat, and the lower edges of said flanges provide the surfaces in supporting engagement with said substantially rigid platform.

9. Apparatus for fabricating a wooden truss, in accordance with claim 8, wherein said slat support means comprises T-bars, having the heads thereof remotely positioned with respect to the stationary platform.

40 10. Apparatus for fabricating a wooden truss, in accordance with claim 9, wherein the heads of said T-bars constitute a center supporting means for each slat and is in engagement with the under surface of each slat.

45 11. Apparatus for fabricating a wooden truss, in accordance with claim 9, wherein a further upwardly and inwardly extending flange projects from each of the lower edges of each of said downwardly and inwardly extending flanges and extends to points below and spaced from the under-surface of said head.

50 12. Apparatus for fabricating a wooden truss, in accordance with claim 6, wherein the longitudinal edge portions of said slats comprise two sections rolled into abutting relationship.

55 13. Apparatus for fabricating a wood truss, wherein a press is used to embed metal truss plates in the wooden members of the truss at the joints thereof, including, in combination a plurality of elongated slats and support means therefor, and the longitudinal edges of said slats being spaced apart, and wherein fixtures are provided and are movable into position abutting and maintaining the wooden members of the truss in their necessary positions, including, in combination, a fixture base plate on which the fixtures are mounted, said fixture base plate being supported on adjacent slats, and means extending through and operable within the space between the longitudinal edges of adjacent slats, said means being connected to said fixture base

plate and in releasable engagement with said adjacent slats.

14. Apparatus for fabricating a wooden truss, in accordance with claim 13, wherein said means includes mechanism engageable with said fixture base plate and

the adjacent slats and said mechanism is operable to hold said fixture base plate against movement relative to said adjacent slats.
